UNITED STATES PATENT OFFICE.

GEORGE V. WILLSON, OF PITTSBURG, PENNSYLVANIA.

WIRE-TWISTING MACHINE.

SPECIFICATION forming part of Letters Patent No. 717,650, dated January 6, 1903.

Application filed June 4, 1901. Renewed June 12, 1902. Serial No. 111,289. (No model.)

To all whom it may concern:

Be it known that I, GEORGE V. WILLSON, a citizen of the United States of America, residing in the city of Pittsburg, in the county 5 of Allegheny, in the State of Pennsylvania, have invented a certain new and useful Improvement in Wire-Twisting Machines, of which the following is a true and exact description, reference being had to the accompanying drawings, which form a part thereof.

My invention relates to machinery for twisting together the ends of wires—such, for instance, as the two ends of a wire formed into a hoop—and specifically my invention 15 is an improvement upon the wire-twisting machine invented by George M. Depew and for which the said Depew has filed an application for Letters Patent, dated May 28, 1901, Serial No. 62,200.

The object of my invention is, in a machine of the character invented by Depew, to provide an improved twisting device which will engage and act upon a smaller length of the wire end, and, further, to provide means for 25 holding the twisting devices in correct alignment during their operation upon the wire.

The nature of my improvements will be best understood as described in connection with the drawings, in which they are illustrated, and in which—

Figure 1 is a plan view of the Depew twisting-machine with my improvements. Fig. 2 is a cross-section on the line 2 2 of Fig. 1. Fig. 3 is a longitudinal section taken on the 35 section-line 3 3 of Fig. 1; Fig. 4, a horizontal section taken on the section-line 4 4 of Fig. 5. Fig. 5 is an end view of one of the heads and its immediate attachments, taken on the section-line 5 5 of Fig. 4. Fig. 6 is a perspective 40 view of one of the twisting-dies which I prefer to employ in connection with the twisting gear-wheel. Fig. 7 is a sectional view of the dies, showing their mode of operating upon the wire; and Fig. 8 is a perspective view of 45 a wire hoop with its ends twisted together in the manner in which the machine twists them.

A indicates the bed-plate or frame of the machine, which, as shown, has a longitudinal slot A', (see Fig. 1,) which at its inner end 50 broadens out into a transverse slot, (indicated at a', Fig. 2.)

A² and A³ are bearings for the main driving-shaft.

B is a raised bearing at the front end of the frame, having a projecting lip of segmental shape, as indicated.

C are bearings secured on the top of the machine, as shown, and serving to support the shafts (indicated at E E.)

D is the main driving-shaft, working in the 60 bearings A² A³, actuated by a pulley-wheel, (indicated at D'), and having loosely journaled upon it the gear-wheel D², which gear-wheel is connected with a clutch member D³, which when shifted in one direction engages 65 the opposite clutch member D⁴ on the shaft D, so that the gear-wheel rotates with the shaft, while when shifted in the other direction, the clutch members being uncoupled, the shaft rotates without affecting the gear-wheel.

E E, as already mentioned, are shafts journaled in the blocks C C, each of said shafts supporting a gear-wheel, (indicated at E' E''), which gear-wheels are in engagement with 75 the gear-wheel D². The shafts E are prolonged toward the front of the machine, terminating in joint members, (indicated at E³ and E⁴.)

F is a pivot supported on a downwardly-projecting extension A⁵ of the frame and supporting in turn the bell-crank lever, (indicated at F' F''), the member F' being in engagement with the clutch member D³ and the other lever-arm F² being connected through a link 85 F³ with a treadle F⁴, which is normally pressed up, as shown, by a spring F⁵.

G G are fixed pivots secured in the frame A and upon which are journaled the inner ends of the arms G³ G⁴, said inner ends being 90 enlarged, as indicated at G' G'', and said enlargements being provided with segmental gears, (indicated at g' g''), said gears being in constant engagement with each other. The arms G³ and G⁴ have formed upon them 95 or secured to them the bearing-heads G⁵ G⁶, vertically slotted, as indicated at g⁵ g⁶, and preferably having the internal contour indicated at G⁷ in Figs. 4 and 5. The bases G⁸ of the heads G⁵ rest upon the bearing B and are 100 formed with inwardly-extending lips G⁹, (see Fig. 3,) which extend under and engage the

outwardly-projecting lip of the bearing B. Preferably forming part of the heads G⁵ are the projecting bearings, (indicated at G⁶,) said bearings supporting the outer ends of the shafts K K, upon which are secured the bevel-wheels K', while the inner ends K² K² of said shafts form joint members, which are coupled with the joint members E³ E⁴ to form universal joints, as shown.

10 H H are bevel gear-wheels which fit in the cavity of the bearing-heads G⁵ and are provided, as shown, with annular bearing plates or flanges H², which project into an annular channel in the head and are held in place by the slotted plates J, secured on the face of the head and slotted, as indicated at J'. The gear-wheels H are preferably made with projecting hubs H⁴, which extend through a circular opening in the plates J and are provided with guideways, (indicated at H³,) which hold the removable twisting-dies, (indicated at I,) said twisting-dies being slotted, as indicated at I', and having the outer lips of said slots projected inward, as indicated at I². The outer faces of the gear-wheels H are recessed, as indicated at H⁵, so as to make the contact between the wheel and the wire as short as practicable.

The machine above described is in its general characteristics the Depew machine already referred to, my invention being confined to the special construction of the heads G⁵ and the gear-wheel H, by means of which I secure the short contact between the wires and the wheels, and also to the provision of the device which holds the heads down upon the bearing B.

In operation the two ends of the wire to be twisted together are inserted in the twisting device through the slots in the heads and wheels. The operator then placing his foot upon the treadle F⁴ couples the gear-wheel D² with the shaft D, which is constantly running, the said gear-wheel transmitting motion through the gear-wheels E' and E² and their described connections to the shafts K K and through the gear-wheels K' to the gear-wheels H H, which are caused to rotate in opposite directions, twisting the loose ends of the wires around the looped portions. As this twisting takes place the heads G⁵ G⁵ move outward, a perfectly synchronous outward movement being secured by the engagement with the segments G' and G², and as soon as the twisting is completed and the wire removed the heads and twisting-dies are brought together by the action of the spring L, which holds the parts normally in the position shown in Fig. 1.

Having now described my invention, what I claim as new, and desire to secure by Letters Patent, is—

1. In a machine for twisting the ends of wires together, the combination of slotted bearing-heads G⁵ G⁵ having the capacity of moving toward and away from each other, with slotted gear-wheels having their toothed faces turned outwardly and having peripheral bearing-flanges on their inner faces supported in said heads, said gears being adapted to twist the wires as described. 70

2. In a machine for twisting the ends of wires together, the combination of slotted bearing-heads G⁵ G⁵ having the capacity of moving toward and away from each other, 75 with slotted gear-wheels having their toothed faces turned outwardly and having peripheral bearing-flanges on their inner faces supported in said heads, and said gears being adapted to twist the wires as described, and 80 having their outer faces within the toothed sections recessed to diminish their contact with the wires.

3. In a machine for twisting the ends of wires together, the combination of slotted bearing-heads G⁵ G⁵ having the capacity of moving toward and away from each other, 85 with slotted gear-wheels having their toothed faces turned outwardly and having peripheral bearing-flanges on their inner faces supported in said heads, their inner faces projected beyond the bearing and their outer faces within the toothed sections recessed. 90

4. In a machine for twisting the ends of wires together, the combination of slotted bearing-heads G⁵ G⁵ having the capacity of moving toward and away from each other, 95 with slotted gear-wheels having their toothed faces turned outwardly and having peripheral bearing-flanges on their inner faces supported in said heads, said gears being adapted to twist the wires as described, and 100 removable slotted twisting-dies I secured on the inner faces of the gear-wheels.

5. In a machine for twisting the ends of wires together, the combination with a stationary bearing B having an outwardly-projecting segmental lip, of bearing-heads G⁵ G⁵ movable to and from each other on bearing B and having inwardly-projecting lips G⁹ in engagement with the segmental lip of the stationary bearing, and slotted rotary wire-twisting mechanism supported on bearings G⁵. 110

GEORGE V. WILLSON.
